INVENTOR

Oreste Biolcati

By *Oreste L. Biolcati*,
ATTORNEY.

UNITED STATES PATENT OFFICE

ORESTE BIOLCATI, OF WEMBLEY, ENGLAND

SAXOPHONE

Application filed June 22, 1929, Serial No. 273,039, and in Great Britain July 17, 1928.

This invention relates to saxophones and more particularly to the key mechanism for playing the notes high D, D $\sharp$, E and F, and the object of the invention is to simplify the usual or present playing of these notes with the side of the left hand.

According to the invention a saxophone is provided with a set of finger plates for playing the notes high D, D $\sharp$, E and F, which are placed near the usual finger plates for the notes low D, E and F and so that they can be operated by the finger tips of the right hand.

In order that the invention may be more readily understood, reference will now be made to the accompanying drawings in which:—

Figure 1 is an elevation looking at the right hand side of a saxophone provided with the new finger plates according to the present invention, many of the ordinary keys and valve plates of the saxophone being removed for the sake of simplicity in illustration.

Figure 2 is a rear elevation of the same partly broken away,

Figure 3 is a view similarly broken away showing a side elevation of the saxophone viewed from the left hand side.

Figure 4 is a detail cross sectional view through the parts for playing high E;

Figure 5 is a detail cross sectional view through the mechanism for operating key d;

Figure 6 is a cross sectional view through the parts for operating key d';

Figure 7 is an enlarged elevation of the intermediate portion of the instrument, and

Figure 8 is a view of the parts of Figure 7 taken at a right angle thereto.

As shown in the drawings, the saxophone is provided with the usual keys d, d' and f for playing the notes high D, D $\sharp$ and F, which keys will be recognized as part of the conventional instrument as at present in use.

According to the present invention the instrument is also provided with a set of key plates 1, 2, 3, 4 which are placed near the usual finger plates for the notes low D, E and F, such as shown in U. S. Patent No. 1,683,219, granted September 4, 1928, to H.

J. Waters. These finger plates are set in

line substantially parallel with the line of the finger plates for the notes low D, E and F and are arranged so that they can be played with the tips of the fingers of the right hand. The spindle or rock shaft 5 which is operated in the conventional instrument by a key accessible to the right hand for playing the note high E by lifting the valve plate 9 is broken at the point 6 and instead of being carried straight down the side of the instrument and fixed at its lower end to a key plate lever as usual is connected by a cranked rod 7 to a short spindle 8 pivotally supported in line with the spindle 5 and adapted to be rocked by the finger plate 3 which thus takes the place of the finger plate usually provided for playing the note high E. As the operation of the finger plate 3 turns the spindle 5 in the opposite direction to that usual, the valve plate 9 is mounted on a separate fulcrum 10 instead of being mounted directly in the spindle 5 as usual and is operated by a tappet lever 11 on the spindle 5 so that it will be opened when this spindle is rocked by depressing the key plate 3.

The key plate 1 is carried by a rock shaft or spindle 12 which is disposed in line with the spindles 5 and 8 and is provided at its upper end with a tappet lever 13 acting through a two-armed lever 14 upon a lever 15 which is fixed to a rock shaft 16 carrying a tappet lever 17 engaging a tappet 18 carried by the valve plate 19 of the key d, so that this valve plate is lifted by the operation of the key plate 1. To accommodate the two-armed lever 14 the rock shaft 20 (which is part of the ordinary known mechanism for operating the octave valve 21 from the key plate 22) is interrupted by a cranked portion 23 which accommodates a spindle 24 disposed in line with the spindle 20. The spindle 24 is spigoted at its ends in the crank plates of the part 23 and the lever 14 is pivotally mounted on the spindle 24. The rock shaft 16 is supported at its lower end by a fulcrum support 26 fixed to the instrument and is spigoted at its upper end to a spindle 27 whose upper end is supported in another fulcrum plate 26 fixed to the instrument.

The spindle 27 carries a two-armed lever 28

adapted to lift the valve plate 29 of the key *d'* and actuated by a lever 30 carried by the spindle 24. The spindle 24 also carries a lever 31 operated by a tappet lever 32 on a cranked rod 33 which is connected at its lower end to a short spindle 34 which carries the key plate 2. The spindle 34 is supported between adjacent ends of the spindles 8 and 12 by spigot and socket joints.

10 The finger plate 4 is arranged to lift the valve plate 35 normally operated by the key *f*. For this purpose advantage is taken of the cranked lever 36 which forms part of the ordinary saxophone and which serves to lift 15 the valve 35 of the key *f* automatically when the key 38 (shown in dotted lines in Figure 1) is depressed. The key plate 4 is carried on the end of a spindle 39 whose upper end carries an arm 40 engaging the lever 36 so that 20 the valve 35 will be lifted when the key 38 is depressed.

15 The key 41 shown in Figures 1 and 2 of the drawings is the auxiliary key usually provided on a saxophone as an alternative method 25 of playing the note middle C by lifting the valve plate 41a. The key 42 is the key for playing the note A $\sharp$ by lifting the valve plate 43. These two keys have their arms bent upwards and sideways as shown so that the key 30 plates will lie over the cranked rod 7 but otherwise they are not different from the keys usually provided on a saxophone for lifting the valve plates 41a and 43.

It will now be seen that of the four finger 35 plates 1, 2, 3 and 4 provided in accordance with the present invention, the plate 1 lifts the valve 19, the plate 2 lifts the valve 29 and the plate 4 lifts the valve 35, whilst the plate 3 takes the place of the finger plate usually provided in line with the finger plates 41 and 42 40 for lifting the valve 9.

In the use of the instrument, the keys *d*, *d'* and *f* may be worked in the ordinary way for lifting the valves 19, 29 and 35 and the 45 key plate 3 for lifting the valve 9. When the operation of the keys *d*, *d'* and *f* becomes difficult, however, as is often the case, the player may use the tips of the fingers of his right hand to work the keys 1, 2 and 4 as an 50 alternative method of lifting the valves 19, 29 and 35.

In order to facilitate the use of these keys it is desirable that the key 1 should be depressed automatically whenever any of the 55 keys 2, 3 and 4 is depressed and for this purpose the plate 1 is provided with an extension 1a which extends under the key plates 2, 3 and 4 so as to be depressed whenever any of these keys is depressed.

60 It will be understood that the keys *d*, *d'* and *f* can be omitted if desired and the keys 1, 2 and 4 relied upon entirely to take their place.

I claim:—

1. In a saxophone, mechanism operable for 65 playing the notes high D, D $\sharp$, E and F hav-

ing a set of finger plates placed near the usual finger plates for the notes low D, E and F so that they can be operated by the finger tips of the right hand.

2. A saxophone provided with mechanism 70 having finger plates for playing the notes D, D $\sharp$, E and F as claimed in claim 1 wherein the said finger plates comprise four plates one of which takes the place of the plate heretofore provided for playing the note high E, such four plates being set in a line substantially parallel with the line of the finger plates for the notes low D, E and F.

3. A saxophone according to claim 1 wherein in the said finger plates comprise four plates one of which takes the place of the plate heretofore provided for playing the note high E, such four plates being set in a line substantially parallel with the line of the finger plates for the notes low D, E and F, 80 one of said finger plates having an extension lying under the other three so as to be operated automatically when any of those three plates is depressed substantially as described.

4. A saxophone provided with a mechanism having a set of finger plates operatively connected with the valves for playing the notes high D, D $\sharp$, E and F located near the tone holes for lower D, E and F.

In testimony whereof I have hereunto set my hand.
